LAUNDRY IRONING MACHINE

Henricus C. A. Zwaard, Rijswijk, Netherlands,
assignor to Machinefabriek Reineveld N. V.,
Delft, Netherlands, a company of the Netherlands

Application October 14, 1948, Serial No. 54,391
Claims priority, application Netherlands
October 27, 1947

6 Claims. (Cl. 38—58)

1

Laundry ironing machines are ordinarily provided with means for varying the pressure exerted by the clothed roller and its polishing bed on one another, reference being had, inter alia, to the British patent specification 58,184. In these known machines the bearings of the roller trunnions are each connected to one member of a telescopic rod, the other member of which is associated with a crank at the corresponding end of a shaft disposed in parallel relation with the roller axis and adapted to be rotated by suitable actuating mechanism, a resilient element such as a spring being interposed between both members of each telescopic rod in such manner as to allow the roller to yield to excessive pressure as may be set up by the passage of abnormally thick wearing apparel. With this construction, the ends of the roller are adapted to yield through different distances, so that the roller may temporarily get out of parallelism with its bed, whereby the cloth of the roller is likely to shift, the consequence being that the thickness of the cloth at one end exceeds that at the opposite end, so that the roller assumes a permanent inclination relative to its bed and the satisfactory operation of the machine is impaired.

The means under review ordinarily also serve for lifting the roller from its bed, although this function could as well be performed by a separate lifting gear.

The present invention, which has for its object to avoid the inconvenience referred to above, is suitable for laundry ironing machines of any description, wherein the bearings of the roller trunnions are associated, through a suitable lever system, with mechanism for lifting and lowering the roller, and it primarily consists herein that all elements of the lever system are rigid and that the said resilient element is interposed in the actuating mechanism. Owing thereto, it is impossible for one end of the roller to move up or down and thereby increase or decrease the tension of the resilient element, without the other end performing an equal movement, abstracting, of course, from possible slight clearances and torsions in the various parts of the pressure controlling means.

Reference is had to the diagrammatic drawing, in which Figs. 1 and 2 illustrate an elevation and an end view, respectively, of a preferred embodiment of the invention, Fig. 3 being an end view of part of a second embodiment.

In Figs. 1 and 2, the clothed roller is designated by 4, the stationary, heated polishing bed by 5. Each of the bearings 6 and 7 of the roller trunnions is pivoted to the top end of a crank rod 8, 9 respectively, the lower end of which is asso-

2

ciated with a crank 10, 11, respectively, keyed to a shaft 12, which extends in parallel relation with the roller axis and is supported vertically below the roller in bearings of the frame of the machine. The crank rods are of equal lengths, and the same is the case with the two cranks, which, moreover, are parallel with one another.

Each bearing 6, 7 is associated with one end of a normally horizontal arm 13, the other end of which is pivoted to the frame. The drawing shows only one of said arms, which are parallel and of equal lengths.

From the foregoing it follows that rotation of the crank shaft 12 causes the roller to perform movement, in parallel relation with itself, in a circular path about the stationary common axis of rotation of the arms 13. Dependent upon the direction of rotation of said shaft, the roller 4 is lifted from, or urged towards its bed 5.

With a view to imparting rotary motion to shaft 12, a segment of a worm wheel 14 is keyed thereto, said segment meshing with a worm 16 keyed to a horizontal, transverse shaft 15. Said transverse shaft, which is provided with a handwheel 15a and is lengthwise movable in bearing blocks 17, 18 secured to the frame, is also provided with a collar 19 adapted to abut against the bearing block 18. Interposed between, and bearing against both worm 16 and bearing block 17 is a coiled spring 20 encircling shaft 15. Bearing 18 is provided with a scale 21 enabling the operator to read the distance from collar 19 to block 18, corresponding to the length of spring 20.

Let us assume the various parts of the machine to be so adjusted that, with the bed loaded exclusively by the weight of the roller, collar 19 engages block 18 and spring 20, in unloaded condition, engages both the block 17 and the worm 16. If handwheel 15a is now turned in the proper direction, the shaft 12 will be rotated in anti-clockwise direction as seen in Fig. 2, whereby the bed will be gradually relieved from load and the roller will eventually be lifted therefrom, its axis remaining parallel to the bed. The pressure exerted by segment 14 on worm 16 holds collar 19 in engagement with block 18, spring 20 remaining unloaded. If, thereupon, handwheel 15a is turned in opposite, i. e. clockwise direction, the roller 14 will first descend until original conditions are restored, whereupon worm 16, in conjunction with the transverse shaft 15, is gradually moved to the left so as to load spring 20. The pressure of loaded spring 20 is transmitted, as an additional ironing pressure in excess of the weight of the roller, to the latter through the medium of worm 16, segment 14, shaft 12, cranks 10, 11 and rods 8, 9. Said additional ironing pressure can

be read from scale 21 and is adapted for fine adjustment. In known ironing machines, the pressure exerted by the roller on its bed rather suddenly increases, from zero to a maximum value, from the moment wherein the descending roller engages its bed, so that accurate adjustment of said pressure is difficult to realize.

Fig. 3 shows that the collar 19 on shaft 15 as illustrated in Fig. 2, is substituted by a coiled spring 22 interposed between worm 16 and block 18. Be it assumed that the machine is so adjusted that, with the worm 16 in a position corresponding to zero on scale 21, the weight of roller 4 supported by bed 5 is just compensated by spring 22.

If, now, handwheel 15a is turned in the direction required for lifting the roller, the latter immediately begins to rise. Subsequent rotation of the handwheel in the opposite direction will first restore the initial conditions, whereupon the weight of the roller will be gradually transmitted to the bed 5, spring 22 being gradually relaxed and spring 20 being gradually compressed. The moment wherein the full weight of the roller has been transmitted to the bed, the tension of spring 20 begins to act as an additional ironing pressure. In this embodiment, scale 21 indicates the absolute value of the ironing pressure.

Owing to wear and tear of the cloth whereby the roller is coated, the cranks 10, 11 will gradually move downward through a very slight angular distance. However, the ironing pressure is always determined by the length of spring 20, so that any one of the divisional lines of scale 21 will always correspond to one and the same value of said pressure.

Without departing from the scope and the spirit of the invention, the cranks 10, 11 may be substituted, for instance, by eccentrics, and movement of the transverse shaft 15 may be transmitted to shaft 12 by means of a crank on the latter, said crank having a slot engaged by a pin on the transverse shaft, in which case the crank should be spring loaded. Furthermore, the two springs drawn in Fig. 3 may be substituted by one single spring, which through part of its stroke, is put under tension and through another part is compressed. Again, the coiled springs may be replaced by rubber buffers, or by counterweights. If the roller is supported in stationary bearings, its bed should be adapted to be moved towards the roller by means of the lever system and the mechanism described hereinbefore.

What I claim is:

1. In a laundry ironing machine including a supporting frame, a stationary ironing member and a movable ironing member movably mounted on said frame so as to be adapted to be raised and lowered and engaging said stationary ironing member in a lowered position, an operating arrangement for said movable ironing member, comprising in combination, an operating member mounted in said supporting frame movable in two opposite directions corresponding to raising and lowering of said movable ironing member, respectively; and motion-transmitting means positively connecting said operating member with said movable ironing member for raising the latter, and including resilient means resiliently connecting said operating member with said movable ironing member during lowering the latter, so that when movement of said movable ironing member is blocked by said stationary ironing member, said movable ironing member is resiliently pressed against said stationary iron-

5 ing member during further movement of said operating member in a lowering direction.

2. In a laundry ironing machine including a supporting frame, a stationary ironing member and a movable ironing member mounted on said supporting frame so as to be adapted to be raised from an operative position engaging said stationary ironing member into an inoperative position spaced therefrom and to be lowered from said inoperative position to said operative position, an operating arrangement for the movable ironing member, comprising in combination, worm gear means rotatably mounted on said supporting frame; positive motion-transmitting means operatively connected at one end to said worm gear means and at the other end to said movable ironing member so that said worm gear means is adapted to turn in lowering direction only during lowering of said movable ironing member but is blocked by said motion-transmitting means from further turning in lowering direction after said movable ironing member has reached its lowered position engaged by said stationary ironing member; worm means mounted in said supporting frame rotatably and slidably in axial direction and meshing with said worm gear means so that said worm gear means permanently tend to slide said worm means in one axial direction due to the weight of said movable ironing member transmitted to said worm gear means by said motion-transmitting means, said worm means being rotatable in raising direction resulting in turning of said worm gear means in raising direction, and in lowering direction resulting in turning of said worm gear means in lowering direction; stop means limiting sliding movement of said worm means in said axial direction; turning means for turning said worm means in raising and lowering directions, turning of said worm means in raising direction while in engagement with said stop means resulting in its turning without axial sliding movement, while turning of said worm means in opposite direction will first result in turning of said worm means in lowering direction without sliding thereof until further turning of said worm gear means is blocked, and then result in turning of said worm means combined with sliding in opposite axial direction out of engagement with said stop means; and resilient means mounted on said frame engaging said worm means and urging the same in said axial direction at least when the same has slid out of engagement with said stop means in said opposite axial direction, said resilient means thus exerting pressure in said axial direction on said worm means which will be transmitted through said worm gear means and said motion-transmitting means to said movable ironing member increasing the closing pressure of the same.

3. In a laundry ironing machine including a supporting frame, a stationary ironing member and an ironing roller adapted to engage said stationary ironing member, an operating arrangement for said ironing roller, comprising in combination, bearing means rotatably supporting said ironing roller at its ends and being movably mounted on said supporting frame so as to permit raising and lowering of said ironing roller, said ironing roller being blocked by said stationary ironing member in a lowered position; a first shaft turnably mounted in said supporting frame substantially parallel to the axis of said ironing roller; motion-transmitting means pivoted at one end thereof to said bearing means

and at the other end thereof eccentrically connected to said first shaft; a worm gear fixedly secured to said first shaft; a second shaft extending normal to said first shaft mounted in said supporting frame rotatably and axially movably; means for rotating said second shaft; a worm fixedly secured to said second shaft and meshing with said worm gear on said first shaft, the weight of said raised ironing roller urging said second shaft in one axial direction until said ironing roller is blocked by said ironing member; and resilient means arranged between the supporting frame and said worm and being compressed when said second shaft moves in an axial direction opposite to said axial direction while said ironing roller and thereby said worm gears are blocked, whereby resilient pressure is exerted by said ironing roller on said stationary ironing member when said second shaft and said worm are rotated.

4. In a laundry ironing machine including a supporting frame, a stationary ironing member and an ironing roller adapted to engage said stationary ironing member, an operating arrangement for said ironing roller, comprising in combination, bearing means rotatably supporting said ironing roller at its ends and being movably mounted on said supporting frame so as to permit raising and lowering of said ironing roller, said ironing roller being blocked by said stationary ironing member in a lowered position; a first shaft turnably mounted in said supporting frame substantially parallel to the axis of said ironing roller; motion-transmitting means pivoted at one end thereof to said bearing means and at the other end thereof eccentrically connected to said first shaft; a worm gear fixedly secured to said first shaft; a second shaft mounted in said supporting frame rotatably and axially movably; means for rotating said second shaft; a worm fixedly secured to said second shaft and meshing with said worm gear on said first shaft, the weight of said raised ironing roller urging said second shaft in one axial direction until said ironing roller is blocked by said ironing member; resilient counterbalance means abutting at one end against said supporting frame and at the other end thereof against one end of said worm; and resilient means abutting at one end against said supporting frame and abutting with its other end against the other end of said worm and being compressed when said second shaft moves in said axial direction opposite to said axial direction while said roller and thereby said worm gear are blocked, whereby resilient pressure is exerted by said ironing roller on said stationary ironing member when said second shaft and said worm are rotated.

5. In a laundry ironing machine including a supporting frame, a stationary ironing member and an ironing roller adapted to engage said stationary ironing member, an operating arrangement for said ironing roller, comprising in combination, a pair of bearing means rotatably supporting said ironing roller at its ends and being pivotally mounted on said supporting frame so as to permit raising and lowering of said ironing roller, said ironing roller being blocked by said stationary ironing member in a lowered position; a first shaft turnably mounted in said supporting frame substantially parallel to the axis of said ironing roller; a pair of crank shafts pivoted to said pair of bearing means; a pair of cranks

fixedly secured to said first shaft and operatively connected to said pair of crank shafts; a worm gear fixedly secured to said first shaft; a second shaft extending normal to said first shaft mounted in said supporting frame rotatably and axially movably; means for rotating said second shaft; a worm fixedly secured to said second shaft and meshing with said worm gear on said first shaft, the weight of said raised ironing roller urging said second shaft in one axial direction until said ironing roller is blocked by said ironing member; limiting movement of said second shaft in said axial direction; and resilient means arranged between the supporting frame and said worm and being compressed when said second shaft moves in an axial direction opposite to said axial direction while said ironing roller and thereby said worm gear are blocked, whereby resilient pressure is exerted by said ironing roller on said stationary ironing member when said second shaft and said worm are rotated.

6. In a laundry ironing machine including a supporting frame, a stationary ironing member and an ironing roller adapted to engage said stationary ironing member, an operating arrangement for said ironing roller, comprising in combination, bearing means rotatably supporting said ironing roller at its ends and being movably mounted on said supporting frame so as to permit raising and lowering of said ironing roller, said ironing roller being blocked by said stationary ironing member in a lowered position; a first shaft turnably mounted in said supporting frame substantially parallel to the axis of said ironing roller; motion-transmitting means pivoted at one end thereof to said bearing means and at the other end thereof eccentrically connected to said first shaft; a worm gear fixedly secured to said first shaft; a second shaft mounted in said supporting frame rotatably and axially movably; means for rotating said second shaft; a worm fixedly secured to said second shaft and meshing with said worm gear on said first shaft, the weight of said raised ironing roller urging said second shaft in one axial direction until said ironing roller is blocked by said ironing member; stop means limiting movement of said second shaft in said axial direction; resilient means arranged between the supporting frame and said worm and being compressed when said second shaft moves in an axial direction opposite to said axial direction while said ironing roller and said worm gear are blocked, whereby resilient pressure is exerted by said ironing roller on said stationary ironing member; and indicating means mounted on said supporting frame adjacent to said second shaft measuring the axial displacement in said opposite direction of the latter and indicating the amount of resilient pressure exerted by said ironing roller on said stationary member.
